(57) **CLAIM**

The ornamental design for a fairing, as shown and described.

DESCRIPTION

FIG. 1 is an environmental view showing the fairing on an aircraft;

FIG. 2 is a front perspective view of the fairing;

FIG. 3 is a right side view of the fairing; and

FIG. 4 is a plan view of the fairing.

FIG. 5 is a front view of the fairing; and,

FIG. 6 is a rear view of the fairing.

The dashed lines in FIG. 1 form no part of the claimed design.
